OIL PUMP

Adolph W. F. Manzel, Buffalo, and William C. H. Pfeil, Ebenezer, N. Y., assignors to Manzel Bros. Co., Buffalo, N. Y., a corporation of New York

Application January 2, 1932, Serial No. 584,404

7 Claims. (Cl. 184—27)

Our invention relates to improvements in oil pumps, and more particularly to what may be termed "force-feed lubricators" for use in connection with machinery of various kinds.

5 One of the objects of our invention is the provision of a simple and effective oil pump or lubricating device, which will positively force the lubricating material to the parts to be lubricated in predetermined quantities; individual pumping 10 units being provided which are adapted to be connected to the respective parts to be lubricated.

Another object of our invention is to provide new and novel means for maintaining one of 15 the piston plungers of a pumping unit in adjusted position, and thereby assure the feeding of a predetermined quantity of oil from the pumping unit of which the piston plunger forms part.

20 Another object of our invention is to provide new and novel means for actuating the primary plunger of the device and to provide means for establishing and maintaining any degree of idle motion for the same during the operative 25 stroke of the actuator before causing actuation of said plunger.

With the above objects in view, our invention consists in the novel features of construction, and in the arrangement and combination of parts 30 to be hereinafter described and more particularly pointed out in the subjoined claims.

The accompanying drawings illustrate our invention.

Fig. 1 is a side elevation of our improved lubricating device.

Fig. 2 is an enlarged transverse section taken on line 2—2, Fig. 1.

Fig. 3 is a fragmentary horizontal section taken on line 3—3, Fig. 2; the section being 40 taken through one of the pumping units or elements only.

Fig. 4 is a horizontal section taken on line 4—4, Fig. 2.

Fig. 5 is a horizontal section taken on line 45 5—5, Fig. 2.

Fig. 6 is a vertical section taken on line 6—6, Fig. 2.

Fig. 7 is a vertical section taken on line 7—7, Fig. 2.

50 Fig. 8 is a vertical section through a portion of a pumping unit or element, through the outlet coupling and the removable valve cages; the section being on the same plane as Fig. 2, but showing the lower valve cage provided with a by-pass.

Fig. 9 is an enlarged bottom view of one of the valve cages.

Fig. 10 is a plan view of one of the resilient valve-retainers.

Having reference to the drawings in detail, 5 Fig. 1 designates a casing which, although shown rectangular in form, may be otherwise shaped, and while the device is capable of pumping or feeding lubricant of various kinds we will hereinafter, for convenience of description, refer to 10 to the lubricant as oil. The casing serves as a container for the oil, which may be introduced into the container to any desired level.

The casing or oil container comprises a bottom wall 12, side walls 13, and end walls 14. The 15 side and end walls have inwardly-directed flanges 15 at their upper ends and a cover 16 is applied to the open upper end of the casing or container, the flanges 15 being held rigid by a comparatively thick backing plate 17 applied to the 20 under side thereof.

The cover is provided with a filling tube 18, which opens into the casing and is closed at its upper end by a lid 19 hinged thereto; this arrangement providing a convenient means for 25 supplying the casing or container with oil. The cover is also provided with a large opening 20 through which one or more pumping units or elements 21 extend. In Fig. 1 we have shown two such units or elements. Each pumping unit 30

includes a casting, preferably comparatively narrow and long; each casting being disposed transversely and having its ends resting upon the cover at opposite sides of the opening 20. Through the extremities of each pumping unit 35 or element, fastening screws 22 are passed; these screws being passed through the cover 16 and through opposite flanges 15 and being threaded into the backing plate 17 applied to the under side of the flanges. In this manner the pumping units or elements can be easily introduced into the casing, or removed therefrom for 40 repairs or replacements, as may be found necessary. Each of said castings, or pump casings as they may also be termed, projects into the 45 oil casing or container and is provided with two depending portions 23, 24, respectively, and vertical bores 25, 26 are reamed or otherwise formed in the pump casing so that they extend centrally through the projections 23, 24, respectively; the 50 bore 26 having its upper portion enlarged to form a well 27, and the upper end of this enlargement or well is screw-threaded and further counterbored to form an upwardly-facing shoulder or gasket seat 28. A hollow combined clo-

55

sure and stop cap 29 is threaded into the upper screw-threaded portion of the well 27, and has an outstanding flange 30, between which and the upwardly-facing shoulder or gasket seat 28 a 5 gasket 31 of desired thickness is placed, which is compressed upon tightening the closure and cap 29 so as to prevent leakage of oil at this point.

By enlarging the upper portion of the bore 26, 10 an upwardly-facing shoulder or valve seat 32, preferably upwardly flared, is provided therein; said seat having a ball valve 33 normally seated thereagainst. While the ball valve may be of sufficient weight to assure its proper seating, we 15 preferably arrange above the same a weight and stop pin 34 which extends into the hollow cap 29, and is prevented from tilting measurably by the wall of said cap, especially since the upper end of said pin is diametrically enlarged within the 20 cap; the lower end of said pin being preferably concaved so that it conforms to the ball valve on which it rests. Upward movement of this weight and stop pin is limited by the top wall of the hollow cap 29, and consequently the opening movement 25 of the ball valve is correspondingly limited.

The pump casing is vertically bored from its lower surface upwardly, as at 35, and the upper end of this vertical bore 35 is in communication with the bore 26 through the medium of a horizontal passage or port 36. 30

Threaded into the bore 35 from the bottom of the pump casing is a nipple 37, the bore of which is flared at its upper end to provide a seat for a ball valve 38 which closes the upper end of the 35 nipple. An inlet pipe 39 is secured to the lower end of the nipple 37 and extends downwardly to a point near the bottom of the casing where it is screw-threadedly entered into a nipple 40 fitted into a valve cage or casing 41. This valve cage 40 or casing has a valve seat 42 formed therein from which an inlet opening 43 extends downwardly through the under side of the valve casing.

The nipple 40 is notched or slotted at its inner end, as at 44, and within the valve casing 41 45 a ball valve 45 is arranged, which normally is seated against the valve seat 42, and when drawn upwardly will engage the lower end of the nipple 40 and may close the bore thereof; however, oil entering the valve casing under suction is drawn upwardly through the nipple 40 and inlet pipe 39, by reason of the notches or slots 44 remaining uncovered by the valve. The valve being of 50 smaller diameter than the interior diameter of the valve casing permits oil to pass around it and enter the nipple through the notches or slots 44. 55 In order to strain the oil before entering the valve casing 41, it is passed through a foraminous sheath or hood 46 placed over the valve casing and secured thereto by means of a wire 47, or in any other approved manner.

The lower or small portion of the bore 26 serves as a plunger cylinder, which may be so referred to at times hereinafter, and this cylinder has its upper end normally closed by the valve 33. When said valve is unseated said plunger 60 cylinder opens directly into the oil well 27.

Within said cylinder a piston plunger 48 is reciprocably arranged, and the passage or port 36 opens into said cylinder between said piston plunger and the valve 33. The piston plunger 70 has an outstanding contact flange 49 at its lower end and it is frictionally retained within the cylinder by a spring tension or brake-device 50, best illustrated in Fig. 5. This spring tension-device 75 is in the form of a U-shaped spring 51, having

at opposite ends friction pins 52 secured thereto which are passed through diametrically opposite openings 53 in the cylinder and bear with their free ends against the plunger 48. These friction pins preferably have their inner ends concaved 5 to conform to the peripheral surface of the piston plunger and they may be riveted or otherwise secured to the U-shaped spring 51. Due to the nature of the tension applied by said U-shaped spring, the friction pins are held under 10 pressure against the plunger at diametrically opposite points so as to equalize the resistance applied to the plunger in opposing directions. The equal forces applied to the friction pins by the spring and the fact that the ends of the pins are 15 concaved prevent movement of the plunger against the cylinder wall in a direction at right angles to the line of pressure applied by the pins 52, and assures an absolutely direct or straight-line travel for the plunger. Moreover, it maintains the plunger in any position within the cylinder at which it may be stopped, until force is applied to the plunger in an upward or downward direction by suitable actuating means.

For the actuating means we utilize a shaft 54, 25 which has suitable bearing in the ends walls of the oil casing or container 11, and in order that the lubricating device may be actuated either manually or mechanically, said shaft extends out a suitable distance from each end of the casing. 30 At one end it may have a handle 55 applied thereto, which is loosely mounted on the shaft and is capable of being clutched to the shaft by means of a pin 56 extending from the shaft at diametrically opposite points and adapted to be 35 entered into a notch or notches 57 in the hub of the handle; to accomplish which the handle may be slid lengthwise on the shaft. Any other means for operating the shaft may be employed, if desired. 40

To the opposite projecting end of the shaft 54, a crank arm 58 may be secured, which may be caused to travel in a circular path, or through an arc of a circle, suitable connection with an operating medium being made for this purpose. 45 Any other way of mechanically rotating the shaft 54 may, however, be resorted to. On the shaft 54 within the casing 11, a cam or cams are arranged, the cam or cams being secured to the shaft in any approved manner so as to rotate 50 therewith. Although our improved lubricating pump will generally include more than a single pumping element or unit, there will, of course, be actuating mechanism for each such element or unit. 55

Straddling the cam 59, or each cam, as the case may be, is an actuator yoke 60 which has a lateral extension 61 in which is adjustably threaded a screw stud 62 extending axially from the lower end of an actuator sleeve 63. Said actuator sleeve 60 is guided on a guide pin 64 extending through the pump casing 21 from its upper end; said guide pin being rotatably mounted in said pump casing and having at its upper end a head 65 which bears against the upper side of said casing and has a 65 kerf 66 formed therein to permit of its being easily rotated by applying a screw-driver or other suitable tool thereto. Any other form of head may be used so long as the guide pin can be rotated within the pump casing. In order to maintain the 70 head 65 of the guide pin firmly against the upper surface of the pump casing, a washer 67 is applied to the guide pin, and a spring disk 68 interposed between the washer and the under side of the pump casing; said washer 67 being held 75

against downward movement by a cotter or other pin 69 passed through the guide pin.

At the lower end of the guide pin a key pin 70 is arranged, said key pin being passed diametrically through the guide pin and projecting from opposite sides thereof. The actuator sleeve 63 is provided with vertical slots 71 at diametrically opposite points which extend downwardly from the upper end of said sleeve a considerable distance; and the projecting ends of the key pin 70 are entered in said slots, so that upon rotation of the guide pin within the pump casing, the actuator sleeve 63 will be rotated, moving simultaneously therewith either downwardly or upwardly along the guide pin. In this manner the space between the under side of the actuator sleeve and the actuator yoke is either enlarged or diminished in size. The actuator sleeve 63 is adapted to bear against the upper side of the outstanding flange 20 on the piston plunger 48, and to assure a firm contact of said actuator sleeve against said outstanding flange over a considerable area, said sleeve is also provided with an outstanding flange or contact element 72 at its lower end which overlies the contact flange of the piston plunger 48, as clearly shown in Fig. 2.

In the pump casing 21, an angular passage 73 is arranged, one end opening into the oil well 21 above the valve 33, and its other end opening to the upper surface of the pump casing, at which point a gooseneck pipe 74 is connected thereto, the inlet end of said pipe being threaded or otherwise secured in the upper end of said angular passage, while the outlet end thereof terminates a distance above the upper surface of the pump casing.

Directly beneath the outlet end of said gooseneck pipe, a well 75 is formed in the pump casing, and opening into the bottom of this well is the vertical member or portion of an angular passage 76, the horizontal member or portion of which opens into the bore 25, the lower portion of which serves as a cylinder for a piston plunger 77 secured to the actuator yoke 60. The piston plunger 48 serves as the primary plunger while the piston plunger 77 serves as a secondary or feeding plunger. The horizontal member or portion of the angular passage 76 opens into the bore 25 above the secondary or feeding plunger 77. The bore 25 has a stepped enlargement at its upper end, the upper portion of said enlargement being screw-threaded to receive a coupling 78 having an axial passage 79 therethrough and in the space between said coupling and a shoulder 80 formed in the bore, a predetermined distance above the outlet of the angular passage 76, renewable or replaceable valve cages 81, 82 are arranged. These cages are disposed one above the other, the upper lying in contact with the lower, and the lower receiving support from the shoulder 80. The upper cage enters a depression 83 formed in the under face of the coupling 78.

Each of these valve cages is bored axially and counterbored, and in the wall of the counterbored portion, resilient valve retainers 84 are arranged, each valve retainer being formed of wire curved into open ring form, as at 85, Fig. 10, and the ends of the wires being directed inwardly to provide resilient fingers 86 which bear against ball valves 87 arranged in the valve cages and seated in the smaller portions of the bores of said cages, which portions are flared upwardly to prevent the ball valves passing therethrough, yet allow them to enter the flared smaller portions of the bores a predetermined distance and thus make

a tight fit to guard against the passage of oil upwardly beyond the same, except under the application of pressure applied to the oil underneath, which will cause the balls to rise and the fingers 86 of the valve retainers to flex. The open-ring portions of these valve retainers are held in grooves formed in the valve cages and said retainers maintain the ball valves against their seats. When pressure is applied to the ball valves from beneath, they become lifted sufficiently from their seats to permit the passage of oil upwardly into the coupling 78, and through the latter and its connection to the point or points at which it is to be applied for properly lubricating some machine part or parts. For this purpose, a delivery tube 88 used as such connection is inserted into the upper end of the coupling 78 and held clamped thereto in a liquid-tight manner by means of an oppositely-tapered nipple or sleeve 89 and a cap 90 threaded onto the coupling, which forces said nipple or sleeve tightly around the pipe 88 and also tightly against the coupling and the cap.

We have protected the wells 75 formed in the pump casings 21 from dust and dirt, by placing over the same a transparent hood 91, preferably formed of glass and, if desired, this hood may have air-tight contact with the pump casings by securing it thereto in any approved manner.

The guide pin 64 and actuator sleeve 63 jointly serve as a feed regulating device, since upon rotating said guide pin in one direction—say clockwise—the screw stud 62 at the lower end of the sleeve will be moved upwardly within the lateral extension or arm 61 of the actuator yoke. This results in the lower end of the actuator sleeve, or more particularly the flange of said sleeve, moving out of contact with the flange 49 on the primary piston plunger, which may also be referred to as a feed-regulating plunger.

When rotating the guide pin 64 in the opposite direction, or counter-clockwise, the screw stud 62 of the actuator sleeve will be lowered within the extension or arm of the actuator yoke 60, and during this action the piston plunger 48 will be lowered with it.

It may here be stated that the bore through the nipple 37, the port 36, a portion of the bore 26, the angular passage 73, the gooseneck pipe 74, the well 75, the angular passage 76, a portion of the bore 25, the bores through the valve cages 81 and 82, and the bore in the coupling 78 constitute an oil conduit, to one end of which the inlet pipe 39 is secured, and to the other end of which the outlet or feed pipe 88 is secured. It will, of course, be understood that certain portions of this conduit or passage with extensions thereof are utilized as cylinders for the primary or feed-regulating piston plunger 48 and the secondary or feeding plunger 77.

It is to be noted that the regulation of the length of the stroke of the primary or feed-regulating piston plunger 48 in an upward direction determines the quantity of oil to be delivered out through the delivery tube 88. Consequently, the lowering of said piston plunger results in an added quantity of oil being delivered from the lubricating device; the quantity of oil delivered being in exact accordance with the range of upward movement of said piston plunger.

To guard against the ball valves 87 rising within their cages and closing the conduit portions directly beyond, or as shown, above, in the event that the resilient fingers 86 become broken, we

have provided means to by-pass the oil around the valve.

As clearly shown in Figs. 2 and 8, the inner wall of the depression 83 formed in the under face of the coupling 78 is provided with a diametral groove 92, which intersects the inlet of the bore 79 in said coupling. If for any reason the fingers 86 of the resilient valve retainer 84 become broken in the upper valve cage, the valve 87 therein rising and engaging the coupling will be of insufficient size to close the diametral groove 92, with the result that the oil under pressure will pass around the ball valve and enter the bore 79 of the coupling through the end portions of the groove.

We have provided the under side of the upper valve cage 81 with a similar diametral groove 93, which intersects the bore of said valve cage so that in the event the resilient fingers become broken, oil will pass upwardly through the upper valve cage, even though the valve 87 in the lower cage rises against the upper valve cage and closes the bore thereof; the action being exactly as described with reference to the diametral groove 92 in the depression of the coupling 78.

In order that all valve cages may be made alike and be replaceable, we have illustrated in Fig. 8 the arrangement of by-passes just described, and in addition thereto, such a by-pass or diametral groove 94 is also provided in the under side of the lower valve cage 82. While, when so used, the by-pass in the lower valve cage serves no purpose, as there is no valve beneath it capable of closing the passage therethrough, it, however, dispenses with the use of valve cages of two different constructions, and they therefore may be used interchangeably, each valve cage being usable either as the upper or lower cage.

It is, of course, understood that any number of pumping units or elements may be employed, and that they will all operate in the same manner; the shaft 54 having a cam mounted thereon for each pumping unit or element. An explanation of the operation of a single unit will therefore suffice for all.

Upon rotation of the shaft 54, the cam 59 thereon will be rotated, and as this cam, which is in the form of a disk, is eccentrically mounted on the shaft, it will cause the actuator yoke 60 to move upwardly and downwardly in a vertical plane, this being due to the piston plunger 77 and actuator sleeve 63 being secured thereto and serving as guides to restrict the actuator yoke to a straight line movement. The upward and downward movement of this actuator yoke results in a corresponding movement of the actuator sleeve 63 and of the piston plunger 77, and as the lower end of the sleeve 63 overlaps the flange 49 on the primary or feed-regulating piston plunger 48, said piston plunger is caused to move downwardly with the actuator sleeve; during which movement the valve 33 is drawn firmly against its seat under suction created in the cylinder above said piston plunger, which also draws upon the ball valve 38 and unseats it so that oil is drawn upwardly through the valve cage 41 and inlet pipe 39, and into the cylinder above the piston plunger 48, thus completely filling the space above said piston plunger.

During the upward movement of the actuator yoke, the actuator sleeve 63 is moved out of engagement with the primary or feed-regulating piston plunger 48, which is retained in its lowermost position by the spring retainer device 50. The actuator yoke moves upwardly idly a pre-

determined distance before engaging the piston plunger 48, after which further upward movement of said actuator yoke will raise said piston plunger, cause the ball valve 38 to close and the ball valve 33 to open; the oil under pressure in the cylinder above said piston being delivered into the oil well 27 and from the latter through the angular passage 73 for delivery from the gooseneck pipe 74 into the well 75 of the angular passage 76, the oil then enters the cylinder 10 above the feeding piston plunger 77, which during its upward stroke forces the oil through the valve cages, out through the outlet coupling 78 and into the delivery pipe 88, which directs it to the desired point or points to be lubricated.

It is, of course, understood that the accumulation of oil within the angular passages 76 and 73 is drawn into the cylinder of the feeding piston plunger 77 upon the downward stroke of said plunger.

Our invention is susceptible to various changes or modifications, many of which fall fully within the scope of the appended claims without departing from the spirit of our invention or sacrificing any of the advantages thereof.

Having thus described our invention, what we claim is:

1. In an oil pump, the combination of a cylinder, a piston plunger reciprocable within said cylinder, means for actuating said piston-plunger with lost motion between the two, and a friction device engaging said piston plunger peripherally at diametrically opposite points only.

2. In an oil pump, the combination of a cylinder, a piston plunger reciprocable within said cylinder, actuating means for reciprocating said piston plunger with lost motion between the two, and a friction device carried by said cylinder acting against said piston plunger at diametrically opposite points thereof.

3. In an oil pump, the combination of a cylinder, a piston plunger reciprocably arranged within said cylinder, actuating means for reciprocating said plunger with lost motion between the two, and a friction device including a U-shaped spring having contact elements extending through the wall of said cylinder and engaging said piston plunger at diametrically opposite points.

4. In an oil pump, the combination of a cylinder, a piston plunger reciprocably arranged within said cylinder, actuating means for reciprocating said piston plunger with lost motion between the two, and a friction device including a spring having friction pins passed through the wall of said cylinder at diametrically opposite points and engaging said piston plunger to exert pressure thereagainst from opposite directions.

5. In an oil pump, the combination of a cylinder having openings through its wall at diametrically opposite points, a piston plunger reciprocably arranged in said cylinder, actuating means for reciprocating said piston plunger with lost motion between the two, a U-shaped spring straddling said cylinder and having friction pins at its extremities passed through said openings and engaging said piston plunger at diametrically opposite points, said pins within said openings serving as the only means of supporting said U-shaped spring.

6. In an oil pump, the combination with a cylinder having openings through its wall at diametrically opposite points, of a piston-plunger reciprocably arranged in said cylinder, means for actuating said piston plunger with lost motion between the two, a U-shaped spring straddling

said cylinder and having friction pins at its extremities passed through said openings, and engaging said piston-plunger at diametrically opposite points, said pins having concaved end faces engaging said piston-plunger.

5. 7. In an oil pump, the combination of a cylinder having an oil inlet and an oil outlet, a piston plunger reciprocable within said cylinder and having a predetermined range of movement

therein to pump a predetermined quantity of oil therefrom, means for actuating said plunger within said cylinder, and a self-adjusting friction device engaging said plunger at diametrically opposite points allowing movement of said plunger only under force applied thereto by said actuating means.

ADOLPH W. F. MANZEL.
WILLIAM C. H. PFEIL.
